UNITED STATES PATENT OFFICE

ALEXANDER S. SPEER, OF BUFFALO, NEW YORK, ASSIGNOR, BY MESNE ASSIGNMENTS,
TO CERTAIN-TEED PRODUCTS CORPORATION, A CORPORATION OF MARYLAND

ROOFING

Application filed November 25, 1925. Serial No. 71,360.

This invention relates to roofing, and among other objects, aims to provide an improved securing means for the roofing, which while perfectly securing the covering to the supporting surface, will permit of sufficient slip of the roofing relatively to the securing means to prevent the material from buckling under the expansion or contraction caused by atmospheric and thermal variations.

10 The nature of the invention may be readily understood by reference to one illustrative construction embodying the invention and shown in the accompanying drawings.

In said drawings:

15 Figure 1 is a plan view of a typical individual shingle provided with the illustrative securing means.

Figure 2 is a plan view showing a surface laid with said shingles.

20 Figure 3 is a perspective view of one element of said securing means.

Figure 4 is a perspective view of the cooperating element of said securing means.

Figure 5 is a longitudinal cross section 25 through said securing means as applied to shingles but before the final positioning of the shingles.

Figure 6 is a similar cross section through a shingled surface after the shingles have 30 been finally positioned and secured by said securing means.

Figure 7 is a fragmentary transverse section of a shingled surface showing the cooperating securing elements on the underside of 35 a shingle.

Figure 8 is a fragmentary plan view showing said securing means attached to the underside of a shingle.

In the drawings, 10 designates a typical 40 shingle formed with projections or tabs 11 and 12, which, in this instance have converging sides 13 and extended in opposite directions from the sides of the body 14 of the shingle; such tabs, in this instance, being 45 dissimilar. The projection 11 may be called for convenience, a triangular tab. The body of the shingle is also formed with lateral projections 15 and 16. The tab 15 is advantageously provided with a nail aperture 17 50 which may be utilized for properly locating

a securing element. The tab 16 is provided with a notch or cut away portion 18 for properly locating an adjacent shingle in a given course. When shingles are laid in courses (see Fig. 2) the extension 15 may be employed to separate the adjacent tabs 12 by spaces 19; the point of extension 15 registering with the notch 18 of the adjacent shingle. When the courses are laid in overlapping relation and staggered (see Fig. 2) 60 so that the sides 13 of the tabs of one course register with the bases of the recesses or spaces 19 of the adjacent lower course, the roofing so laid presents the appearance of a plurality of hexagonal shingles. Hence, the 65 term "semi-hexagonal" has been employed to designate the shape of the lower tab 12 in the illustrative shingle. Variations in the shape of the shingle tabs 11 and 12 produce correspondingly different effects in the appearance of the roof.

The illustrative shingle securing means may be advantageously employed with shingles made from flexible material, to hold down their free ends and to prevent curling 75 of the shingles. The securing means comprise one element in the form of a plate 20 and a cooperating element on the form of a staple 21, which are attached to the underside of the shingle 10.

Plate 20 is rectangular in shape and is provided at one end with a lug 22 which, in this instance, is struck up above the surface thereof and at the opposite end a nail aperture 23 which, in this instance, is pierced 85 therein leaving a burr 24 thereon. The staple 21 is applied to the underside of the shingle over the plate 20 by means of prongs 25, which penetrate the shingle and are upset or bent over as at 26 and embedded in the coating of mineral material, such as slate, which is on the exposed surface.

The staple 21 when applied to the underside of the shingle allows the plate 20 to be 95 held loosely in place thereby allowing a lateral and longitudinal motion. (See Figs. 5, 6, 7 and 8). The lug or prong 22 and burr 24 prevent the plate 20 from slipping from under the staple 21, and lug 22 also serves as a 100

pivot to allow lateral shifting of the plate (see dotted lines of Fig. 8).

In shingling a roof, or the like, with shingles provided with the illustrative securing means, each course is laid by placing a shingle of the next upper course over the shingles on the next lower course. Figs. 5 and 6 show the two stages of attaching the shingle by means of the improved securing means.

10 After the burr 24 of the nail aperture 23 of the plate 20 is inserted in the hole 17 of a shingle of the lower course, a nail is driven through aperture 23 into the sheathing 27. (See Fig. 5.) The shingle 10 is then shifted downward into the dotted line position shown in Fig. 5, such shifting being permitted by the sliding connection between the plate 20 and staple 21. The base of the tab 12 can then be alined with the base of tab 15 of the shingle of the lower course. In this position the plate 20 and its securing nail will be entirely covered by the shingle. (See Fig. 6.)

The securing means is so constructed and arranged that it will not only hold down the shingle material, but will permit the overlying section to shift under expansion and contraction without evidence of buckling or other unevenness or distortion of roof surface.

Obviously the illustrative shingle and fastening means may be varied considerably without departing from the principles of the invention; and the invention is not limited to the details of the illustrative construction. Moreover, it is not indispensable that all the features of the invention be used conjointly; they may be used to advantage in various different combinations and subcombinations.

Having described one embodiment of my invention, I claim:—

- 40 1. A securing means for roofing material comprising a plate adjustably attached to the underside of the material, said plate provided with a nailing and spacing aperture.
- 45 2. A securing means for roofing material comprising a plate provided with a nailing and spacing aperture at one end and a lug at the other adjustably attached to the underside of the material.
- 50 3. A securing means for roofing material comprising in combination a plate provided with a nailing and spacing aperture at one end and a lug at the other adjustably attached to the underside of the material by means of a stapling device.
- 55 4. A roofing element having a securing means applied to its underside composed of a nailing plate and a staple for attaching the plate thereto, said plate being adapted to slide between the roofing element and staple.
- 60 5. A roofing element having a securing means attached thereto comprising two sections, one of said sections being a plate provided at one end with a nailing and spacing aperture and at the other end with a lug, the other of said sections being in the form of a

staple within which the plate is adapted to slide.

6. A securing means for roofing material comprising a thin strip loosely connected to one surface of the material, thereby adapting said material to slide relatively to said strip. 70

7. A securing means for roofing material comprising a thin metal strip attached to said material by a universal connection, thereby permitting universal adjustment of the material in respect to the strip after the securing means is fixed to a roof. 75

8. A clip for a roofing element, comprising a body portion ported at one end to receive a nail and constructed at the other end to shiftably interengage with the roofing element and a staple attached thereto. 80

9. A securing link for roofing material attached to the underside thereof comprising a thin metal strip adapted to be nailed to a surface, said link constructed to permit universal movement of said material. 85

10. The method of forming a roofing which consists in providing securing means on the underside of shingles with a nailing portion projecting beyond the margin of the shingles, nailing the securing means on the roof, and adjusting the shingles to cover the securing means. 90

11. The method of forming a roofing which consists in providing securing means adjustably attached to the underside of shingles with a nailing portion adapted to project beyond the margin of the shingles, nailing the securing means on the roof, and sliding the shingles to cover the securing means. 95 100

In testimony whereof I affix my signature.
ALEXANDER S. SPEER.
